ELECTROLYTIC REGENERATION OF SPENT CAUSTIC

Peter J. Gaylor, Union, N. J., assignor of one-half to Charles W. Rippie, Summit, N. J.

Application December 10, 1949, Serial No. 132,274

12 Claims. (Cl. 204—153)

1
This invention relates to the regeneration of spent caustic obtained when scrubbing sour gasoline for removal of oxidizable sulfur compounds such as mercaptans, hydrogen sulfide, and the like. More specifically, it deals with an electrolytic process for converting said sulfur compounds to readily removable oxidation products, such as to disulfides, in a simple and effective operation.

The regeneration of spent refinery caustic at the present time is a tedious and costly operation and entails use of large, expensive equipment, including heat exchangers, as well as contamination of the atmosphere. In the removal of mercaptans, the spent caustic is blended with some oxidation catalyst, such as tannic acid, and the mixture is then blown with air and steam until most of the mercaptans (present as mercaptides) are converted to disulfides, which are skimmed off as an oily layer floating on top of the regenerated caustic. In some cases, the regenerated caustic thus recovered is given an oil wash to complete removal of the disulfides before the caustic is returned to the naphtha scrubbing operation.

In the present process, the spent caustic is merely passed through an electrolytic converter wherein the sulfur compounds such as mercaptans are converted to oxidation products such as disulfides, without the need of air, catalyst, steam, heat exchangers, etc. and since these latter materials are not employed, there is little, if any, atmospheric contamination involved. Furthermore, by-product hydrogen is produced during the conversion, which may be used in the processing operations, as will be hereinafter set forth.

The invention will be more readily understood by reference to the drawings which illustrate a preferred embodiment of the invention. Figure 1 shows a diagrammatic flowsheet of the processing steps involved, while Figure 2 is a perspective view taken from the rear of one filter press type of electrolyzer which may be employed for the conversion operation. Front views of the different plates employed in the electrolyzer depicted in Figure 2, are shown in Figures 3, 4 and 5. Similar numerals refer to similar parts in the various figures.

Referring again to the drawings, numeral 1 represents a scrubbing tower in which sour gasoline (preferably caustic—washed sufficiently to remove most hydrogen sulfide, if present) is fed into the bottom through line 2 while aqueous caustic solution (preferably 15—20%) is fed into the top through line 24, countercurrent to the

gasoline stream. The sweetened gasoline is removed from scrubber 1 through line 3, while the spent caustic, containing mostly mercaptan impurities, is drawn off the bottom through line 5 and thence through line 6 into surge tank 7. Pump 9 draws the caustic from tank 7 and feeds it through line 10 into liquid-gas reservoirs 12 and 36 disposed on top of electrolyzer unit 13. Lines 11 and 25 are by-pass lines for the surge tank and pump respectively.

2
Electrolyzer 13 is of the filter-press type, having anode plates 29 alternately disposed with respect to cathode plates 31, with insulating diaphragm plates 30 interposed therebetween. Anode and cathode plates 29 and 31, respectively, are preferably made of nickel plated iron or graphite and have an outer sealing edge 85 and 63 respectively, and ridged front and back faces 43 and 64, the valleys of the ridges being below the plane of outer sealing surfaces 85 and 63, thereby enabling liquid caustic to travel and migrate therein when the plates are tightly compressed against each other. The intermediate diaphragm plate 30 has a rubber sealing edge 55 disposed around the outer edge of the plate on both faces, the surface making a tight seal against surfaces 85 and 63 of the adjacent and oppositely disposed electrode plates. The central portion 56 of the diaphragm plate 30 is made of asbestos or other suitable diaphragm material, enabling liquid to liquid conductive contact therethrough, but resisting diffusion therethrough of gases formed by the electrolysis of the caustic solution.

All of the plates are provided with an opening in each of the four corners. However, some of these openings are sealed off from fluid within certain of the plates. For example, in anode plate 29 (Fig. 3), the portion of the caustic solution which forms the anolyte in each cell entering through opening 47 flows freely onto the plate surface 43, most of the liquid flowing in the valleys between the ridges. During electrolysis, nascent oxygen forms at the anode plate 29, and, if mercaptans are present, this oxygen immediately reacts therewith to produce disulfides. With proper operation, there should be no excess oxygen produced. However, if some is formed, it will rise in the valleys of the surface of the plate and migrate into top opening 46 and pass through the corresponding (right hand upper) openings in all of the plates, thence through header pipe 38 and into collector tank 36, from which it may be drawn off for any purpose desired.

Electrolyzed anolyte and any excess oxygen flows over surface 43 of plate 29 and passes through opening 46 since sealing edge 50 is not closed off at inner portion 51, thereby permitting egress of liquid from surface 43 into opening 46, even though all of the sealing edges 50, 58, 69, etc. are in contact with each other as shown in Fig. 2.

Diaphragm plate 30 is made of tightly woven asbestos cloth, the central portion 56 being permeable to liquid but impermeable to gas (particularly when wet). Edges 55 of plate 30 are impregnated with rubber and lined with a rubber, Neoprene, or plastic or other suitable film to facilitate a tight seal between plates and eliminate leakage of liquid or gas. All of the corner openings 57, 59, 60 and 61 are sealed off at the inner portion 60 to prevent any liquid from entering these openings 57, 59, etc. from plate surface 56, although liquid and gas from other plates can migrate through openings 57, 59, etc.

Cathode plate 31 is constructed similarly to plate 29 and is provided with flat front and back sealing edge surfaces 63. However, in the case of the corner openings in plate 31, the sealing edges of the openings are disposed so that the portion of the caustic solution which forms the catholyte in each cell will flow in through the right hand lower opening 13 (opposite to the liquid inlet in plate 29). This catholyte then flows over the valleys, between the ridges on surface 64 and the regenerated caustic passes out through diagonally disposed opening 65, due to the sealing edge 66 being partly open at inner portion 61. Hydrogen formed during the electrolysis also flows out, along with the catholyte, through the upper left-hand openings 65 in all of the plates.

Accordingly, regenerated caustic and gaseous electrolytic products are discharged through the upper corner openings of the plates, the oxygen, if any, collecting, in this case, in the right hand corner openings, and gradually accumulating in reservoir 36, while hydrogen passes through the left hand corner openings and eventually collects in reservoir 12 from which it may be drawn for any use required therefrom.

Regenerated caustic leaving electrolyzer 13 through valve 16 and line 17 is run or is pumped into settling tank 18 wherein aqueous regenerated caustic 20 settles out at the bottom, while the disulfides form an oily layer 19 which may be drawn out of tank 18 through line 11. The regenerated caustic 20 may then be drawn out of tank 18 through line 21 and pumped by pump 22 through line 23 back into caustic line 24 in 55 the gasoline scrubbing operation. Fresh caustic, in small replenishing amounts, may be fed in through line 4 or line 80.

Hydrogen formed in the electrolysis may be collected in chamber 12 and drawn off through line 79 for use in any of the desired refinery operations.

Although the Shriner filter press-type electrolyzer has been described for effecting conversion of the mercaptans to disulfides, other types of electrolyzers may be used, particularly those adapted to produce hydrogen and oxygen, and therefore provided with permeable diaphragms between the electrodes, since it is essential to keep the hydrogen and oxygen separated. The term "mercaptan" employed herein also includes mercaptides, in which form the mercaptans are present when reacted with caustic. Also, although caustic soda is specified in the examples

set forth, it is understood that potassium hydroxide is not precluded as the treating agent.

Regenerated caustic, containing the oxidized sulfur compounds (in this case disulfides), passes through the upper corner openings and is collected and drawn off through valve 16 and line 17.

As can be deduced from Figure 2, rear header 26, which also comprises a portion of the frame of the filter-press type unit, is provided with upper channels for facilitating collection of the gases passing through corner openings, such as channel 85 for collecting hydrogen from upper left hand openings 57'. In this case, a leader pipe 86 is inserted in reservoir 12, connecting tightly with channel 85 to prevent any leakage or seepage of spent caustic 97 coming in through line 35. Liquid 97 acts as a seal for the hydrogen collected in reservoir 12.

Similarly, lower channels are provided in rear header 26 to allow flow of spent caustic into the lower corner openings of the plates. In Fig. 2, channel 87 is shown for feeding the lower left hand openings in corners 61' of the plates.

Front header 32 is the member against which pressure is applied by hand wheel 33 which turns screw post 83 and thus imposes a thrust on header 32, squeezing the plates between both headers. Front header 32 is provided with channel 84 for draining regenerated liquid from both upper corners of the plates and leading said liquid through valve 16 and line 11 to outside the electrolyzer.

Lugs 62 are provided on the sides of all plates and these rest on insulated shafts 27 which are supported by supports 42. Positive electrical leads 75 on the positive plates are connected with the positive line lead 14, while the negative leads 88 on the negative plates are led to main negative electrode 14', both main electrodes being fed direct current by a converter, motor generator set, or the like. The electrical connections 41 may be mounted on insulating panel 40 as shown in Figure 2.

Instead of separating the hydrogen from the regenerated liquid, it is also possible to eliminate reservoir 12 (and 36 when no free oxygen is made) and discharge the hydrogen and regenerated liquid through openings 57' (Fig. 2) and channel 84, out into tank 18 (Fig. 1) where the hydrogen may be collected in the top of tank 18 (Fig. 1) and drawn off through line 82 when desired.

Disulfides and other insoluble oxidation products, which are formed by the electrolytic oxidation, are allowed to collect in tank 18 as an upper layer 19 and drawn off through line 11. Naphtha or kerosene may be run into tank 18 as a spray through line 81 to more efficiently remove oily oxidation products from the regenerated caustic. It is possible to make tank 18 in the form of a scrubbing tower to obtain better contacting with naphtha from line 81.

The present method is also effective in regenerating spent caustic containing hydrogen sulfide impurity. One advantageous feature of such a process is the fact that a considerable portion of the hydrogen sulfide is converted to insoluble sulfur which may be filtered off from the regenerated caustic leaving the electrolyzer, or collected as sediment in tank 18. Although electrolyzer 13 heats up somewhat during the conversion operation, the heat is not excessive, although the application of cooling of the plates is not precluded.

It has been found that a high current density is desirable during the conversion, and densities

of over 0.1 ampere per square inch of projected area are preferred. The term "projected area" relates to the overall dimensions of the plate and does not take into consideration the additional surface provided by the ridges on the plate surfaces.

The following examples are submitted for the purpose of illustrating, but not in any manner limiting, the invention heretofore outlined:

Example I

An aqueous 20% solution of sodium hydroxide containing 0.368% mercaptan by weight was electrolyzed in a Shriver type electrolyzer, the plates of which measured 7" x 7". A voltage of 6 volts and amperage of 7 amps, was imposed on the solution for 10 minutes, with a mild flow of caustic flowing between the plates. The regenerated caustic withdrawn from the electrolyzer, and separated from the disulfide produced, analyzed 0.071% mercaptan by weight, showing a substantial removal of the oxidizable sulfur from the spent caustic.

Example II

In the same type of unit as that described in Example I, a 20% aqueous caustic soda solution containing 0.68% mercaptan sulfur (as butyl mercaptan) was electrolyzed similarly for 10 minutes with 3 volts and 2 amps. The mercaptan sulfur on the separated regenerated caustic analyzed 0.57%. After 20 minutes, the mercaptan sulfur analyzed 0.46%, after 35 minutes, 0.35% and after 40 minutes 0.24%, showing that the oxidation of the mercaptans is almost directly proportional to the electrical energy supplied.

Although plain caustic containing oxidizable sulfur compounds which are oxidizable to readily removable or separable products has been disclosed, it is also possible to employ spent caustic containing solutizer reagents, tannic acid, alcholates, phenates, cresylates, naphthenates, isobutyrate, and the like.

One advantage in eliminating reservoir 12 and allowing the hydrogen to collect in tank 18 with the regenerated caustic is that much better control of liquid flow may be obtained over the electrode plates. Furthermore, it is possible (by changing the size of the corner openings, or by employing pressure) to obtain a greater flow of caustic over the cathode or anode plates (as desired), to effect a higher overall efficiency in the conversion operation.

Although a caustic strength of 15-20% is mentioned herein, it is to be understood that other strengths may be employed, particularly more highly diluted solutions, say of 1% to 10%, as an example. The present process would allow such aqueous caustic containing hydrogen sulfide, in free and/or combined form, to be converted in high yields to free sulfur which would be present as a dispersion in the liquid stream leaving the electrolyzer, and which may be removed by settling and/or filtration of said liquid stream.

I claim:

1. The process of regenerating spent aqueous caustic solution containing oxidizable sulphur-containing impurities which comprises passing a stream of the caustic solution through a diaphragm-type electrolytic cell having insoluble electrodes, impressing on said electrodes a current density of such intensity as to liberate nascent oxygen in direct contact with the oxidizable sulphur-containing impurities in the an-

lyte, and maintaining said solution in the cell, while such electrolysis continues, for a length of time sufficient to bring about oxidization of at least a substantial portion of the sulphur-containing impurities thereof.

2. The process of regenerating spent aqueous caustic solutions as defined in claim 1 in which the sulphur-containing compounds are mercaptides and the oxidation products are disulphides, 10 and which includes withdrawing the treated caustic solution from said cell, and separating the disulphides from the withdrawn treated solution.

3. The process of regenerating spent aqueous 15 caustic solutions as defined in claim 2 in which the oxidizable sulphur-containing compounds include hydrogen sulphide and the product of oxidation thereof is sulphur, and which includes withdrawing the treated caustic solution from said cell, and separating the sulphur from the withdrawn treated caustic solution by filtration.

4. The process of regenerating spent aqueous 20 caustic solutions as defined in claim 1 in which the surface of the electrodes exposed to said 25 solution are nickel.

5. The process of regenerating spent aqueous 30 caustic solutions as defined in claim 1 in which the surface of said electrodes exposed to said solution are graphite.

6. The process of regenerating spent aqueous 35 caustic solutions as defined in claim 1 in which the current density is so correlated with the amount of oxidizable sulphur-containing impurities in the caustic solution and the time the solution remains in said cell that substantially all of the sulphur impurities are oxidized without substantial liberation of free oxygen.

7. The process of regenerating spent aqueous 40 caustic solutions as defined in claim 1 in which the current density impressed on the electrodes is at least 0.1 ampere per square inch of projected area.

8. The process of regenerating spent aqueous 45 caustic solutions as defined in claim 1 which includes liberating hydrogen at the cathode and removing the liberated hydrogen along with catholyte.

9. The process of regenerating spent aqueous 50 caustic solutions as defined in claim 8 in which the current density is so correlated with the amount of oxidizable sulphur-containing impurities in the caustic solution and the time the anolyte remains in contact with the anodes that a small amount of free oxygen is liberated, and which includes removing the excess oxygen from the cell along with anolyte.

10. The process of regenerating spent aqueous 55 caustic solutions as defined in claim 9 which includes separating the hydrogen and oxygen, respectively, from the anolyte and catholyte portions of the caustic solution and returning the caustic solution to said cell for further treatment.

11. The process of regenerating spent aqueous 60 caustic solution containing oxidizable sulphur-containing impurities which comprises passing a stream of the caustic solution in a closed system through a plurality of diaphragm-type electrolytic cells having insoluble electrodes, impressing 65 on said electrodes a current density of such intensity as to liberate nascent oxygen in direct contact with the oxidizable sulphur-containing impurities in the anolyte of each cell, and maintaining said solution in said cells, while such electrolysis continues, for a length of time sufficient 70 75

to bring about oxidization of at least a substantial portion of the sulphur-containing impurities thereof.

12. The process which comprises bringing hydrocarbons containing oxidizable sulphur-containing impurities into intimate contact with an aqueous caustic solution, separating from the hydrocarbon the aqueous caustic solution including sulphur-containing impurities taken up from the hydrocarbon, passing a stream of the 10 caustic solution including the oxidizable sulphur-containing impurities through a plurality of dia-phragm-type electrolytic cells having insoluble electrodes, impressing on said electrodes a current density of such intensity as to liberate nascent oxygen in direct contact with the oxidizable sulphur-containing impurities in the anolyte of each cell, maintaining said solution in said cell, while said electrolysis continues, for a length of time sufficient to bring about oxidation of at least 15 a substantial portion of the sulphur-containing impurities of said solution, withdrawing the

treated caustic solution, separating the oxidized sulphur-containing impurities from the withdrawn treated solution, and returning the caustic solution from which the oxidized sulphur-containing impurities were separated for the treatment of further amounts of hydrocarbon.
